MINE LOCOMOTIVE FRAME STRUCTURE

Henry Fort Flowers, Findlay, Ohio

Application October 17, 1939, Serial No. 299,866

9 Claims. (Cl. 105—26)

This invention relates to new and useful improvements in traction vehicles and particularly seeks to provide a novel frame structure for mine locomotives.

It has been found desirable in the construction of mine locomotives to provide frame structures composed of a plurality of frame elements secured together, as by welding, to thereby present a composite unitary frame of great strength, yet which is simple in design.

The primary object of the invention is to provide a unitary frame structure for mine locomotives or the like in which the side and end walls are formed from a plurality of layers of plates, with the layers disposed in superposed relation and welded together, and in which the load, buffer and collision stresses are adapted to be distributed throughout the frame through the medium of longitudinally extending box girders.

Another object of the invention is to provide a frame structure of the character stated which is composed of a plurality of frame elements secured together, as by welding, to thereby present a composite frame of great strength.

Another object of the invention is to provide a structure of the character stated in which no removable frame element fastening devices such as bolts or rivets, are employed.

A further object of the invention is to provide a locomotive frame of the character stated in which ballast can be provided to increase traction effect by merely increasing the number of plates which are superposed in the formation of the frame.

A further object of the invention is to provide a locomotive frame of the character stated which is specifically intended for use in conjunction with axleless trucks on which wheels are mounted in tandem relation.

A still further object of the invention is to provide a locomotive frame of the character stated which is simple in design, rugged in construction, and economical to manufacture.

With these and other objects in view which will more fully appear, the nature of the invention will be more clearly understood by following the description, the appended claims, and the several views illustrated in the accompanying drawings.

In the drawings:

Figure 1 is a top plan view of a mine locomotive frame constructed in accordance with the invention.

Figure 2 is a side elevation thereof.

Figure 3 is a front end elevation thereof.

Figure 4 is a top plan view of the frame, the operating equipment being omitted.

Figure 5 is a side elevation, partly in section, of the frame structure as shown in Figure 4.

Figure 6 is a rear end elevation of the frame, 5 the operating equipment being omitted.

Figure 7 is a transverse section taken on line 7—7 of Figure 5.

Figure 8 is a detailed longitudinal section at the rear end of the frame.

Figure 9 is an enlarged sectional view illustrating a fragment of wall structure.

In the example of embodiment herein disclosed, the invention is illustrated as embodied in a mine locomotive frame A, which includes 15 spaced parallel side walls 5, 5, an arcuate rear end wall 6, and an arcuate front end wall 7.

Each side wall 5 is composed of a plurality of laminae and includes one or more layers of relatively thin plates 8, and an outer plate 9 of 20 greater thickness. The respective laminae are joined together in surface contact, preferably by welding.

Each of the end walls 6, 7 is composed of a plurality of laminae and includes one or more 25 layers of relatively thin plates 10, and an outer plate 11 of greater thickness. Each of the layers 10, 11 is formed from a plurality of relatively small plates, which are butt-welded together. The respective layers 10, 11 are preferably joined 30 together in surface contact by welding. The laminated plates are welded at their edges and ends throughout. They may also be welded at points where extra strength is needed. The surfaces may be welded with a resistance welder, 35 or a hole may be punched through the outer plates and weld built up through the hole by using acetylene or arc welding.

The ends of the front and rear wall sections 6, 7 are butt welded to the adjacent ends of the 40 side wall sections 5 to thereby provide a composite unitary shell for the frame.

The column or loading stresses set up by the weight of the completely assembled frame are carried and distributed throughout the frame 45 through the medium of a pair of spaced parallel longitudinally extending box girders 12, 12 which are constructed in the following manner.

The side walls 5 are cut away from the bottom as at 13 to provide clearance for the trucks, 50 and also to permit the bottom edge of the frame to be disposed as closely as practical to the tracks. See Figure 5.

A bottom plate 14 extends across the full distance between the side walls 5 and has its oppos- 55

ing edges secured thereto by welding. The plate 14 is disposed slightly above the plane of the upper limit of the cut away portions 13 of the side walls 5. See Figures 4 and 5. A pair of parallel, longitudinally extending vertical plates 15, 15 are respectively spaced inwardly from the side walls 5, and have their bottom edges welded to the plate 14 which forms a common bottom for both box girders. Top plates 16, 16 are provided to complete the girders and are respectively welded to the upper edges of each side wall and its adjacent longitudinally extending plate 15.

One or more transversely extending and vertically disposed bulkhead plates 17 may be employed between the plates 15 of the girders 12 and these provide additional strengthening elements which resist lateral deflection of the frame.

It will be observed by reference to Figures 1 and 2 that the spaces defined by the bottom plate 14, the longitudinal plates 15, and the bulkhead plates 17, form shallow wells or hatches in which the electrical contactors and control equipment including resistance units, generally designated B, may be mounted. The wells thus defined are adapted to be closed by a cover (not shown) which fits over a hatch coaming 18 secured to the top plates 16.

The forward end of the bottom plate 14 extends beyond the forward limit of the box girders 12, is bent downwardly to form an inclined panel 19 and terminates in a short vertical panel 20. The bottom edge of the panel 20 is welded to the straight rear edge of a semi-circular floor plate 21 which is welded to the inner face of the front end section 7 and disposed slightly above the bottom edge thereof.

Each end wall section 6 or 7 is provided with a symmetrically disposed slot 22 located above the plane of the floor plate 21, and through which a coupling device 23 is adapted to extend. See Figures 4 to 6, and 8. A forwardly diverging V-shaped guard 24 has its ends welded to the inner face of each wall section 6 or 7, and its lower edge welded to the respective floor plate 21.

A generally arcuate seat 25 extends around the inner periphery of the front wall 7, and rests upon the corresponding guard 24. The seat is welded to the guard and to the front wall 7.

The coupling 23 at the front end has its inner end pivotally mounted on a vertical shaft 26 journaled between the floor plate 21 and the seat plate 25, and is disposed near the apex of the corresponding V-guard 24.

A bracket 27 is provided on the forward face of the front section 7 and serves as a support for a headlight.

The construction of the rear end of the frame is generally similar to that of the front, but a semi-circular plate 28 is substituted for the seat plate 25 provided at the front. The rear wall section 6 is also provided with an aperture 29 through which the beam of a rearwardly projected headlight may extend.

It will be observed that as a result of having the bottom plate 14 common to both box girders and to both side walls, as well as being inclined downwardly at both ends to terminate at the floor plates 21, the coupling and buffer stresses imposed through the couplers will be transmitted through the entire frame and will not be highly localized. See Figures 2 and 7.

A trolley 30 is mounted on each top plate 16 near the forward end thereof.

The various necessary items of manual control equipment such as the controller box, brake han-

dle, etc., are located in the front section, and are so disposed as to be readily accessible from the semi-circular operator's seat 25.

In some instances it may be found desirable to provide cutaway portions 31 in the front wall section 7 to facilitate ingress and egress of the operator.

Four king pin assemblies are dependably mounted on the bottom plate 14, and each includes a king pin 32, and a king pin head sleeve 10 33 carried by a mounting plate 34 welded to the bottom plate 14 and braced against lateral displacement by a plurality of radially disposed inclined struts 35.

It should be noted that the frame is additionally braced across each pair of king pin assemblies by transversely extending bolsters 36, and that the box girders 12 are reinforced at the location of each king pin assembly by both transverse and longitudinal deflection resisting plates 20 37.

In some uses of locomotives employing frames constructed in accordance with the invention, it will be found necessary to add ballast to provide sufficient traction between the locomotive 25 drive wheels and the rails. Whenever such ballast is needed, additional plates can be superposed over the laminae forming the frame body in sufficient quantity to provide the weight desired. By the addition of ballast in the manner described, the weight of the frame can be materially increased with only a slight increase in the bulk of the frame, and at the same time without reducing the space available for the installation of necessary operating or control equipment.

It should be noted that the arcuate front and rear end wall sections materially contribute to safety in the operation of locomotives employing this frame, as there are no projecting corners 40 capable of accidentally contacting mine projections in the event of accidental derailment or the like.

Thus it will be seen that the invention provides a novel frame for mine locomotives or the like 45 which is composed of a plurality of plate elements welded together to form a unitary structure which is simple in design, rugged in construction, and economical to manufacture.

It should be obvious that through the use of 50 laminated side and end wall sections, instead of solid plates, material savings in the cost of production are effected.

It is of course to be understood that the details of structure and arrangement of parts may 55 be variously changed and modified without departing from the spirit and scope of my invention.

I claim:

1. A frame for traction vehicles including 60 spaced parallel side wall portions, front and rear end wall portions joined to said side wall portions, and a bottom, each of said side wall portions comprising at least two laminations or layers of plate disposed in face to face contact, said end 65 wall portions each comprising at least two laminations or layers of plates disposed in face to face contact with each lamination or layer formed from a plurality of plate elements disposed in edge abutting relation, the whole being 70 joined together by welding to thereby form a unitary frame structure.

2. A fully welded unitary frame for traction vehicles including spaced parallel side wall sections, arcuate front and rear end sections and a 75

bottom, said side and end sections comprising at least two laminations or layers of plates disposed in face to face contact, and a longitudinally extending box girder formed in part by the respective side wall section and disposed between said side wall sections and connected thereto and to said bottom whereby the frame is strengthened and stresses due to loading will be distributed throughout the frame.

10 3. A fully welded unitary frame for traction vehicles including spaced parallel side wall sections, arcuate front and rear end sections, and a bottom plate, vertical longitudinally extending plates spaced inwardly from each side wall section and secured to said bottom, and top plates extending from the side walls to the adjacent vertical plate to thereby form a pair of spaced parallel box girders having a common bottom plate and adapted to distribute load stresses throughout the frame.

20 4. A fully welded unitary frame for traction vehicles including spaced parallel side wall sections, arcuate front and rear end sections, and a bottom plate, said side and end sections comprising at least two laminations or layers of plate, each lamination or layer of said end sections being formed from a plurality of plate elements disposed in edge abutting relation, and a pair of spaced parallel stress distributing box girders disposed along said side wall sections, said bottom plate being common to and forming the bottom of both girders.

25 5. A fully welded unitary frame for traction vehicles including spaced parallel side wall sections, said side wall sections having portions cut away from the lower edges thereof to provide clearance for the mounting of trucks, arcuate front and rear end sections, a bottom plate extending between said side walls and being disposed in a plane slightly above the cutaway portion of said side walls, end reinforcing floor plates disposed in said front and rear sections adjacent the lower edges thereof, the front and rear ends of said bottom plate being inclined downwardly 30 toward and terminated at the respective floor plates, and a pair of spaced parallel stress distributing box girders disposed along said sides, said bottom being common to and forming the bottom of both girders to thereby transmit coupling and buffer stresses therethrough.

40 6. A fully welded unitary frame for traction vehicles including spaced parallel side wall sections, said side wall sections having portions cut away from the lower edges thereof to provide clearance for the mounting of trucks, arcuate front and rear end sections, a bottom plate extending between said side walls and being disposed in a plane slightly above the cutaway portion of said side walls, end reinforcing floor plates disposed in said front and rear sections adjacent the lower edges thereof, the front and rear ends of said bottom plate being inclined downwardly 45 toward and terminated at the respective floor plates, a pair of spaced parallel stress distribut-

ing box girders disposed along said sides, said bottom being common to and forming the bottom of both girders to thereby transmit coupling and buffer stresses therethrough, and a plurality of king pin assemblies dependably mounted beneath 5 said girders for connection with axleless driving trucks.

7. A fully welded unitary frame for traction vehicles including spaced parallel side wall sections, said side wall sections having portions cut away from the lower edges thereof to provide clearance for the mounting of trucks, arcuate front and rear end sections, said side and end sections comprising at least two laminations or layers of plate, each lamination or layer of said end sections being formed from a plurality of plate elements disposed in edge abutting relation, a bottom plate extending between said side walls and being disposed in a plane slightly above the cutaway portion of said side walls, end reinforcing floor plates disposed in said front and rear sections adjacent the lower edges thereof, the front and rear ends of said bottom plate being inclined downwardly toward and terminated at the respective floor plates, a pair of spaced parallel stress distributing box girders disposed along said sides, said bottom being common to and forming the bottom of both girders to thereby transmit coupling and buffer stresses therethrough, and a plurality of king pin assemblies 20 dependably mounted beneath 25 said girders for connection with axleless driving trucks.

8. A frame for traction vehicles including spaced parallel side wall portions, front and rear end wall portions joined to said side wall portions, and a bottom, said side and end wall portions each comprising at least two laminations of plates disposed in surface contact with edges abutting, the ends of the plates forming each lamination being staggered out of alignment with the ends of the plates of the opposing lamination, and the whole being joined together by welding to thereby form a unitary frame structure.

9. A fully welded unitary frame for traction vehicles including spaced parallel side wall sections, arcuate front and rear end sections, a bottom plate extending between said side sections and being disposed in a plane above that of the bottom edges of said side wall sections, end reinforcing floor plates disposed in said front and rear sections adjacent the lower edges thereof, the front and rear ends of said bottom plate being inclined downwardly toward and terminated at the respective floor plates, a pair of spaced parallel stress distributing box girders disposed along said sides, said bottom plate being common to and forming the bottom of both girders to thereby transmit coupling and buffer stresses therethrough, and a pair of king pin assemblies 45 50 55 60 dependably mounted beneath each of said girders for connection with axleless driving trucks.

H. FORT FLOWERS,
